UNITED STATES PATENT OFFICE.

JOHN KOSKINE, OF DETROIT, MICHIGAN.

FLYING-MACHINE.

958,747.

Specification of Letters Patent. Patented May 24, 1910.

Application filed June 14, 1909. Serial No. 501,901.

To all whom it may concern:

Be it known that I, JOHN KOSKINE, a citizen of the United States, residing at Detroit, in the county of Wayne and State of Michigan, have invented certain new and useful Improvements in Flying-Machines, of which the following is a specification.

This invention relates to flying machines of the "heavier than air" type, and its object is to provide certain new and useful features in the construction arrangement and combination of parts all as hereinafter more fully described and particularly pointed out in the claims, reference being had to the accompanying drawings in which,

Figure 1 is a perspective view of a device embodying the invention; Fig. 2 a detail of the engine mounting; Fig. 3 a detail of the shiftable bearing; Fig. 4 is a perspective detail of a portion of a propeller wheel; Fig. 5, an enlarged detail of the flaps and their hinged connection to the blades; Fig. 6 is a diagrammatic view showing in side elevation a modified construction; and Fig. 7 is a similar view showing the same in plan with the propellers removed.

As shown in Fig. 1, 1 is a suitable platform or frame work forming a plane which may be constructed in any suitable manner and of any desired material to make a very light and strong structure, a common practice being to make these planes of a very light frame work covered with silk or other fabric to resist the passage of air through the frame. Rising from the platform are two supporting posts 2 held in place by suitable bracing wires and between the upper ends of these posts extend a shaft 3 provided with a screw-thread.

4 is a large propeller wheel secured upon a drive shaft 5 and this shaft passes through a bearing in a suitable supporting frame 6 which extends downward and is pivoted at its lower ends to the platform at the sides thereof. A casting 7 is mounted upon the screw shaft 3 to slide freely thereon and this casting is formed with a bearing for the driving shaft 5. Within a recess in one end of the casting 7 is a worm gear 8 provided with an internal screw-thread to engage the screw-threaded shaft 3, and in a bearing in the casting is mounted a worm 9 in engagement with the worm gear. An operating rod

10 secured to the worm extends downward to near the platform where it is provided with a suitable hand wheel for turning the same so that the operator may turn the worm and thus actuate the worm gear to move the bearing 7 longitudinally upon the shaft 3 and tilt the propeller 4 in relation to the platform. A suitable motor 11 is pivotally mounted upon the platform 1 within bearings 12 upon the platform and the lower end of the shaft 5 has a bearing in the engine casing so that when the shaft is moved by the tilting of the propeller 4 as described, the motor 11 will turn upon its bearings 12 and maintain its position relative to the shaft which is provided with a large gear 13 in mesh with a pinion 14 on the motor shaft. By thus mounting the propeller wheel so that it may be tilted relative to the plane 1, the operator may cause his machine to be raised vertically by the propeller a desired distance and then by changing the relative position of the propeller and plane by tilting the propeller, he may cause a forward movement of the machine.

Pivotaly attached to the rear end of the platform are the two tail pieces or wings 15 which extend rearwardly and laterally from the platform and are each operated by means of a cross bar 16 secured thereto at its pivotal connection with the platform and suitable cables 17 secured to the upper and lower ends of the cross bars are carried forward to suitable winding mechanism indicated at 18 upon the platform so that the operator may by turning the winding mechanism shift the tail pieces as desired independently of each other. These tail pieces may be constructed in the ordinary way, of any suitable light, thin material and are braced from the cross bars 16 by suitable brace wires.

Extending downward from the bottom of the platform or plane 1 is a center board 19 preferably constructed of the same light material as the platform and braced and held in place by suitable brace wires 20. The propeller wheel is also constructed of any very light, thin and strong material with an axial hub 21 for securing the wheel to the shaft 5 and around this hub is a hollow drum 22 with an open lower end. A peripheral band or rim 23 forms the outer

edge of the rim and extending between this rim and the drum 22 is a series of suitable inclined fan blades 24 which are secured at their ends to the drum and rim to make a 5 light and strong structure. A series of independently movable flaps 25 is pivotally attached to the lower edge of each fan blade by suitable hinges 26 which are formed with stops 27 to limit the opening of the flaps. 10 When the wheel is revolved in the proper direction air will pass between the blades past these flaps which are normally held open by gravity. But if for any reason the wheel should be stopped from rotation while 15 the machine is in mid air, as soon as the machine begins to descend the pressure of air beneath the wheel will at once turn these flaps up against the next adjacent blade, thus closing the air passages between the 20 blades and the wheel will then form a parachute to check the descent of the machine. An outwardly and downwardly curved flange 28 may be provided upon the lower edge of the rim 23 to assist in trapping the 25 air when the wheel performs the function of a parachute. As shown in Fig. 1, the shaft 5 may be extended upward and suitable brace wires 29 attached to its upper end and extended radially outward and made 30 fast to the upper edge of the rim 23 to strengthen the wheel. Similar brace wires 30 may also be attached to the lower edge of the flange 28 and extended radially inward and made fast to a collar on the shaft. 35 In Figs. 6 and 7 a modified construction is illustrated. In this construction the plane or platform 31 is made much greater in length and a series of driving shafts 32, four in number being illustrated, are mounted in 40 suitable fixed bearings on the platform and extend upward therefrom at a forward inclination, suitable brace rods or frame work 33 being provided to hold the shafts rigidly in position. An engine 34 is geared to one 45 of the shafts to turn the same and motion is transmitted from the shaft actuated by the engine to the other shafts by means of belts or chains 35 engaging sprockets or pulleys upon the shafts, said belts being crossed between the shafts so that said shafts will be 50 revolved in opposite directions and the propellers 4 which are secured to their upper ends, will be oppositely turned.

Secured to the lower side of the plane 55 or platform 31 is a suitable supporting frame work 36 arranged to support the machine with the platform in an inclined position when at rest upon the ground as shown.

Steering wings 37 similar in form and 60 construction to the tail pieces 15 are pivotally attached to cross shafts 38 secured to the platform and extend along each side of said platform. These wings are also provided with cross bars 39 similar to the bars 65 16, and these bars on the two wings at each

side are connected together by wires or cables 40 so that when one of the wings is turned the other will be similarly moved. The cross bars 39 for operating the rear wings are attached or secured to suitable 70 sleeves 41 on the cross shaft 38 and suitable gearing indicated at 42 is provided to turn the sleeves independently of each other so that the operator may manipulate the wings at one side of the machine independently of those at the other side. When the machine is in mid air its course may be changed, as to turn to the right, by lowering or turning the wings upon the right side of the machine downward so that the air will strike 80 their lower side and the machine will thus be tilted thereby and by raising or lowering the wings at both sides equally, the machine may be directed upward or downward in its course. 85

It is obvious that various changes may be made in the construction and the mechanism for actuating the parts without departing from the spirit of my invention, and I therefore do not limit myself to any particular 90 form or construction of operating mechanism.

Having thus fully described my invention what I claim is:

1. A machine of the character described 95 comprising a plane, a propeller shaft carried by said plane and extending upward therefrom, and a propeller wheel upon the upper end of said shaft comprising blades, means for automatically closing the spaces between 100 the blades upon rapid downward movement of the machine, and an outwardly and downwardly extending flange attached to the outer ends of said blades.

2. A machine of the character described 105 comprising a plane, a propeller shaft extending upward from said plane, a propeller wheel having a hub portion secured to said shaft, an outer rim portion, blades connecting the rim portion and the hub portion, an 110 outwardly and downwardly extending flange on the lower edge of the rim, a series of gravity flaps attached to the lower edge of the blades, and means for actuating the wheel.

3. In a machine of the character described 115 a plane, a propeller shaft and a propeller wheel upon said shaft comprising a hub portion secured to the shaft, a rim, blades extending between the rim and hub portion, an outwardly and downwardly curved flange on 120 the lower edge of the rim, a series of gravity flaps upon the lower edge of each blade, and stops to limit the movement of the flaps.

4. A machine of the character described 125 comprising a plane, a motor pivotally mounted upon the plane, a propeller shaft mounted in bearings on the motor to turn therewith and extending upward therefrom, a propeller wheel upon the upper end of the shaft, a bearing for the shaft near the wheel, 130

a support for the bearing, means for adjusting the bearing upon its support to move the shaft and turn the same upon the pivotal support of the motor, wing members having 5 narrow forward ends pivotally attached to the plane and rear ends of a width equal to or greater than the width of the plane, and means for adjusting the wide rear ends of

the planes above or below the surface of the plane.

In testimony whereof I affix my signature in presence of two witnesses,

JOHN KOSKINE.
